UNITED STATES PATENT OFFICE.

WILLIAM E. DAVIS, OF JERSEY CITY, NEW JERSEY.

ELECTRO-MAGNET FOR SIGNALS.

SPECIFICATION forming part of Letters Patent No. 327,536, dated October 6, 1885.

Application filed April 24, 1885. Serial No. 163,264. (No model.)

To all whom it may concern:

Be it known that I, WILLIAM E. DAVIS, a resident of Jersey City, in the county of Hudson and State of New Jersey, have invented an Electro-Magnet for Electric Signals, of which the following is a full, clear, and exact description, reference being made to the accompanying drawings, in which—

Figure 1 is a side elevation of my improved electro-magnet. Fig. 2 is a front view of the same. Fig. 3 is a top view of the same. Fig. 4 is a side view of a modification of the same, and Fig. 5 is a top view of the modification.

This invention relates to a new electro-magnet for use in operating a signal or the like.

The invention consists in combining an electro-magnet with projecting pole-pieces of peculiar form, above which the armature, having convex lower surface, is adapted to rotate or oscillate, as hereinafter described.

By means of my improved instrument the armature which carries the signal will be turned into one position whenever the circuit is closed, and automatically turned back by a suitable spring into another position whenever the circuit is open, provided one single electro-magnet is used, while if two magnets are used the position of the signal will depend entirely upon the current that passes through either one of said electro-magnets.

With more particular reference to Figs. 1, 2, and 3, the letter A therein represents an electro-magnet fixed upon a suitable stand, B, in which stand an upright shaft, C, carrying a signal, D, is swiveled. This upright shaft carries the armature E, which is a bar having convex lower face, and adapted to extend over the centers of the two spools of the electro-magnet A, as shown by dotted lines in Fig. 3.

To each of the spools of said electro-magnet, at the pole ends thereof, is secured a projecting bar, F, of iron or analogous material, which bar has an inclined upper face, so that it is highest near the spool and lowest where farthest away from its spool. A little spring, a, draws the shaft C so as to normally hold the armature E in the position in which it is represented by full lines in Fig. 3—that is to say, with its ends above those parts of the

projecting bars F F which are farthest away 50 from their respective spools.

When a current is passed through the electro-magnet A, the arms F F will both be magnetized, and will draw the armature E toward the spools. The inclined upper faces of the 55 bars F F, co-operating with the convex lower side of the armature E, serve to draw the armature gradually into alignment with the spools—that is, into the position shown by dotted lines in Fig. 3. As long as the current 60 lasts the armature will remain in this position—that is, above the spools. The moment the current is interrupted the spring a will exert its influence, and will draw the armature E back into the full-line position which 65 is shown in Fig. 3.

The shaft C may carry a signal, D, which, when the current is established, will indicate "danger," and when it is interrupted it will indicate "safety."

When the parts are in the position shown by full lines in Fig. 3, the distance vertically between the armature and the arms F will be greater than when in the position shown by dotted lines in that figure. The power of the 75 magnet upon the armature is increased as the armature approaches the cores of the electromagnets.

In Figs. 4 and 5 I have represented the invention duplicated—that is to say, I have 80 shown two electro-magnets, A and G, of the same kind as the electro-magnet A, which is shown in Fig. 3. The electro-magnet A of the modification has the projecting arms F F, that extend toward the electro-magnet G, and 85 the electro-magnet G has similar arms, H H, that extend to the electro-magnet A.

What I claim is—

The electro-magnet A, having projecting arms F F, inclined on their upper sides, in 90 combination with the armature E, which is above said arms, and which has a convex lower face, substantially as described.

WILLIAM E. DAVIS.
